OIL BURNER CONTROLLING APPARATUS

Charles P. Vetter, Berkeley, Calif.

Application September 5, 1933, Serial No. 688,180

5 Claims. (Cl. 236—26)

This invention relates to oil burners, and particularly to automatic apparatus for controlling the supply of oil, water and steam or air thereto.

The principal object of my invention is to provide apparatus of relatively simple construction to regulate the feed of oil to a burner and the accompanying elements required to modify and atomize the oil in predetermined proportions, which proportions remain substantially constant under all working conditions of the boiler.

A further object of the invention resides in the provision of pressure controlled apparatus of novel construction and arrangement for actuating in unison the valvular system supplying the various elements required to support combustion, said apparatus being responsive to variations in pressure of the boiler and varying the feed of said elements to the fire to maintain the working conditions of the boiler in substantial uniformity.

A still further object of the invention is to provide automatic operative apparatus particularly adapted to supply and control elements of atomization and combustion to oil burner of the type described and claimed in United States Letters Patent No. 1,823,012, dated September 15, 1931, issued to Peter G. Vetter.

Other objects and advantages residing in my invention, and objects relating to details of construction and arrangements of parts thereof, will be fully set forth in the detailed description to follow.

The accompanying drawings illustrate by way of example a representative form of my invention, in which:

35 Figure 1 is a view in side elevation of apparatus embodying my invention, shown attached in operative condition to a boiler.

Figure 2 is a view in front elevation of a portion of the same.

40 Figure 3 is a similar view in plan.

Figure 4 is an enlarged detached view in vertical section of the pressure controlling apparatus.

45 Figure 5 is a view in longitudinal vertical section of an oil burner adapted to be utilized in connection with my apparatus.

Figure 6 is a fragmentary view in horizontal longitudinal section of the same.

50 Referring to said views and particularly to Figures 5 and 6, the reference numeral 10 indicates the chambered body of an oil burner substantially similar in construction and plan of operation to that described in the aforesaid prior patent. Said body includes steam and oil chambers 11 and 12, respectively, divided by a partition 13.

A tubular casing 15 is connected to the body at the opposite end of the chamber 11 having a burner tip 16 at its opposite end. An oil-feed pipe 17 is connected in the partition 13 to communicate with the chamber 12 and extends centrally of the casing 15 to adjacent its end where it is provided with an outlet-tip 18 within the burner tip 16. The casing 15 and pipe 17 are spaced apart to form an annular passage 20 for the flow of steam from the chamber 11 past the 10 oil outlet-tip 18 to the orifice 21 of the burner-tip.

To the rear of the chamber 12 of the body 10 a nipple 22 extends through the rear of the body having a bore 23 in axial alignment with the casing 15. Said nipple is counter-bored to rigidly receive the outer end of a water supply tube 25 which extends through the chamber 12 and longitudinally within the oil-pipe 17 to provide a passage 26 thereabout for the oil, and terminates in an inner extremity 27 formed with an end 20 aperture and a plurality of apertures 28 spaced apart along its length. A slip-tube 29 is slidably movable within the bore of the pipe 17 and its inner end may be adjusted about the end of the tube 25 to close a desired number of the apertures 28 to afford the area of such openings to furnish the proportion of water deemed advantageous to mix with the oil. The structure thus outlined will be found described at length in said prior patent.

30 Referring to Figure 1, 30 indicates an electric motor to whose power-shaft 31 an oil-pump 32 and air-blower or any suitable compressor 33, are operatively connected. The blower may be disconnected from the power-shaft by a clutch, 35 indicated at 35. The outlet of said blower is connected by a pipe 36 with a branch inlet connection 37 of the body 10 communicating with the chamber 11. A steam-supply pipe 38 provided with a valve 39 is connected at one end 40 by a T-fitting 40 with the pipe 36 and thus communicates with said body chamber and at its other end leads to a source of steam-supply, such as the steam-chest, not shown, of the boiler 41 with which the oil burner apparatus is associated and shown in operative relation thereto in said view. A valve 42 is interposed in the pipe 36 to close the latter pipe when steam is being supplied to the burner sufficient for atomization of the oil and the use of air is not further 45 desired. A pipe 43 provided with a valve 45 is branched from the steam-supply pipe 38 and is connected in a tapped opening 46 in the body 10 leading into the oil chamber 12 and serves to conduct steam under pressure therein and 50 55

into the oil passage 26 so that when required any stricture or stopping of the passage or outlet may be cleared by blowing a jet of steam therethrough.

5 Fuel oil of a suitable grade is supplied to the burner under pressure from the pump 32 through a pipe 47 screw-threaded at its other end in an opening 48 in the body 10 leading into the chamber 12 opposite the pipe 43. From thence the oil flows through the passage 26 of the pipe 17, as has been described.

10 Water under city-main or other pressure is supplied through a pipe 49 connected to the outer end of the nipple 22 from whence it flows through the bore 23 and tube 25 to mingle with the oil, as described. A cut-off valve 50 is interposed in said water supply pipe.

15 Each of the pipes 38, 47 and 49, for steam, oil and water, respectively, is provided with a regulating valve, of the gate or other suitable type, for governing the flow of liquid to the burner. Said valves, indicated by the numerals 51, 52 and 53, respectively, are all provided with valve stems 55 directed in parallel and in the same direction 20 upon each of which a toothed pinion 56, 57 and 58 is respectively keyed, all of said pinions lying in the same vertical plane and in perimetrical toothed engagement with a gear-wheel 60 keyed upon a shaft 61. Said shaft is rotatably mounted 25 in a bracket 62 rigidly secured about the exterior of the body 10 and is provided on its opposite end with a hand-wheel 63 through which the coordinated valves 51, 52 and 53 may be opened or closed under certain conditions to be explained. The meshed engagement of said pinions with said gear actuates all of said valves in unison and the extent of relative opening or closing of the valves will be proportional to the relative number of teeth formed therein, so that the 30 supply of liquid passed through the several valves will remain in constant ratio. Thus with the actuating gear provided with 60 teeth the steam oil and water controlling pinions 56, 57 and 58, will be formed with approximately 25, 30 and 40 35 teeth, respectively.

40 Keyed to the opposite end of the shaft 61 is a pulley-wheel 64 about which a chain or belt 65 is passed and secured. The belt 65 also extends and is secured about a pulley-wheel 66 keyed upon 45 a rock-shaft 67 rotatably mounted in brackets 68 rigidly secured on the boiler-front or any other suitable support.

45 Apparatus is provided to control the actuation of said coordinated valves through operative connection with said rock-shaft, and consists (see especially Fig. 4) of a cylinder 70 provided with a piston 71 therein connected to an end of a rod 72 which is engaged at its other end in a slotted lever 73 keyed on said rock-shaft and which may 50 be disconnected therefrom through a removable clevis-pin 74. Said piston is yieldingly maintained in its upper-most position by means of a coiled spring 75 in said cylinder wherein said coordinated valves for supply of steam, oil and water 55 are opened to their predetermined extreme open condition.

55 One end of the cylinder 70 is closed by a head which is provided with two branch ducts or passages 71, 71', the first being a supply branch and the other an exhaust branch, and both communicating with the cylinder through a common passage-way 76. The passage-way 71 is connected with a pipe 78 controlled by a valve 78' with the steam-chest, not shown, of the boiler to furnish steam pressure upon the top of the piston 75

71 and in opposition to the spring 75 to depress said piston in the cylinder against the tension of said spring in proportion to the excess of pressure and thereby actuate the rock-shaft and close the valves controlled by the gear 60 to a proportionate degree. Said duct, however, is provided with a valve 79 having a valve-closure and stem 80 therefor normally closed under action of a spring 81. Said valve-stem is operatively engageable by an adjustable screw 82 carried by a lever 83 pivotally mounted at 83' and connected by a rod 84 at one end whose other end is connected centrally of a pressure responsive diaphragm 85 mounted in a well-known manner in a housing 86, supported by said pipe 78. It will be noted that said pipe 78 is partially supported by said head. The steam-chamber 87 above said diaphragm communicates with the steam pipe 78 and receives the steam pressure of the boiler to effect the distortion downwardly of said diaphragm with consequent movement of the rod 85 as determined by the tension of a spring 88 adjustably arranged between the diaphragm and a nut 89. At the end of the duct 77 opposite to the valve 79 an escape valve 91 is provided to admit of the release of pressure in the cylinder 70 upon the return of the lever 82 to its normal medial position with consequent closing of the valve 79, the opening of the valve 91 is effected by an adjustable screw 92 carried by an arm 30 93 of the lever 83 and operative when the diaphragm is relieved of excess pressure.

95 Keyed upon the rock-shaft 67 are lever-arms 92 and 93, connected by rods 95 and 96, respectively, with an ash-pit or other draft regulating damper 97 and a flue-damper 98 in the flue 99, whereby said dampers are opened or closed in unison and in response to steam pressure as it affects the diaphragm 85 and piston 71.

100 The operation of my regulating apparatus will be readily understood from the foregoing description. In brief résumé, it will be seen that in starting operations when no or insufficient steam is obtainable from the boiler and the rock-shaft 67 has been disconnected from operative connection with the rod 72 through the removal of the clevis-pin 74 the blower 33 is connected to the motor 30 by the clutch 35 to supply a sufficient working pressure of air through the pipe 36 to the chamber 11 and thence through the passage 20 to the burner tip, to there cause the atomization of the oil and water issuing from the tip 18 and blow the same through the orifice 21, the oil and water thus combined with the air enters the combustion chamber in a combustible mixture which may be readily ignited to support an efficient flame.

105 During such preliminary operations the steam, oil and water valves 51, 52 and 53 are regulated in unison by means of the hand-wheel 63 which will also set the dampers in approximately correct position. As soon as steam has been generated in the boiler to a sufficient pressure to actuate the diaphragm 85 the rod 72 is again connected with the lever 73 of the rock-shaft, the clutch 35 is disconnected, and the valve 42 is closed to establish the automatic control of the oil burner.

110 When the valve 78' is opened the steam pressure of the boiler will be communicated to the diaphragm 85 and when the pressure is in excess of the combined resistance of the diaphragm and the tension of the spring 88 the valve 79 will be pushed open to admit steam into the cylinder 70 and thus activate the piston 71 and 75

rod 72 in opposition to the spring 75 to rock the shaft 67 and thus rotate the gear 60 to open the supply valves 51, 52 and 53 accordingly. Similarly increase and reduction of pressure above a minimum working pressure will react immediately upon the inlet valves for the supply of steam, oil and water at whatever ratio they may be set and regulate such supply in unison and in pre-determined proportions.

10 I claim:—

1. An oil burner control apparatus comprising valves for controlling the supply of oil, steam and water respectively to a burner, a rotatable operating member, means for so connecting said valves and said operating member that the valves are actuated simultaneously therewith in a pre-determined ratio with respect to each other, a rotatable actuator operatively connected with said operating member, a cylinder, a head closing one end of said cylinder, said head having an inlet and an exhaust passage communicating with the interior of the cylinder through a common passage-way, a normally closed valve also mounted on said head and controlling said inlet passage, a steam conduit having its discharge end connected with said inlet passage, a piston in said cylinder operatively connected with said actuator, means normally tending to move the piston toward said head, pressure responsive means supported by said steam conduit and in communication therewith so as to be responsive to the steam pressure within said conduit, and means operated by said pressure-responsive means for unseating said valve when the steam pressure reaches a predetermined maximum.

2. An oil burner control apparatus comprising valves for controlling the supply of oil, steam and water respectively to a burner, a rotatable operating member, means for so connecting said valves and said operating member that the valves are actuated simultaneously therewith in a pre-determined ratio with respect to each other, a rotatable actuator operatively connected with said operating member, a cylinder, a head closing one end of said cylinder and having an inlet and an exhaust passage communicating with the interior of the cylinder through a common passage-way, a piston in said cylinder operatively connected with said actuator, means normally tending to move the piston toward said head, a steam conduit having its discharge end connected with said inlet passage, normally seated valves independently controlling the inlet and the outlet passages, a pressure-responsive device supported by said steam conduit and in communication therewith, and means connected with said pressure-responsive device for selectively unseating said valves at predetermined pressures in said conduit.

3. An oil burner control apparatus comprising valves for controlling the supply of oil, steam and water respectively to a burner, a rotatable operating member, means for so connecting said valves and said operating member that the valves are actuated simultaneously therewith in a pre-determined ratio with respect to each other, a rotatable actuator operatively connected with said operating member, a cylinder, a head closing one end of said cylinder, said head having an inlet

passage and an exhaust passage communicating with the cylinder through a common passage-way, normally seated valves controlling the respective passage-ways, a lever pivotally mounted on said head and provided with means to engage and unseat said valves, a piston in said cylinder operatively connected with said actuator, means normally tending to move the piston toward said head, a steam conduit supported by said head and having its discharge end connected with said inlet passage, a pressure-responsive device supported by said steam conduit and communicating therewith, and means connecting said pressure-responsive device with said lever.

4. An oil burner control apparatus comprising valves for controlling the supply of oil, steam and water respectively to a burner, a rotatable operating member, means for so connecting said valves and said operating member that the valves are actuated simultaneously therewith in a pre-determined ratio with respect to each other, a rotatable actuator operatively connected with said operating member, a cylinder, a head closing one end of said cylinder and having a central passage-way therein provided with lateral supply and exhaust branches, normally closed valves supported by said head and controlling said branches, a lever pivotally mounted upon said head in such manner that the ends thereof overhang said valves, a piston in said cylinder operatively connected with said actuator, means normally tending to move the piston toward said head, a steam conduit supported by said head and having its discharge end connected with one of said branches, a pressure-responsive device supported by said steam conduit and communicating therewith, means connecting said pressure-responsive device with said lever, and abutment screws in the ends of said lever positioned to engage said valves.

5. An oil burner control apparatus comprising valves for controlling the supply of oil, steam and water respectively to a burner, a rotatable operating member, means for so connecting said valves and said operating member that the valves are actuated simultaneously therewith in a pre-determined ratio with respect to each other, a rotatable actuator operatively connected with said operating member, a cylinder, a head closing one end of said cylinder and having a central passage-way therein provided with lateral supply and exhaust branches, normally closed valves supported by said head and controlling said branches, a lever pivotally mounted upon said head in such manner that the ends thereof overhang said valves, a piston in said cylinder operatively connected with said actuator, means normally tending to move the piston toward said head, a steam conduit supported by said head and having its discharge end connected with one of said branches, a chamber supported by said steam conduit and communicating therewith, a diaphragm extending across said chamber, means for normally and yieldably holding the diaphragm in a predetermined position, and a rod connected to said diaphragm and said lever.

CHARLES P. VETTER.
